CLAIM

The ornamental design for a lug cleaning applicator, as shown and described.

DESCRIPTION

FIG. 1 is a side plan view of our ornamental design for a lug cleaning applicator. The broken lines in the drawing represent environmental structure only and form no part of the claimed design.

FIG. 2 is a top view of our design. The broken lines in the drawing represent environmental structure only and form no part of the claimed design.

FIG. 3 is a bottom view of our design. The broken lines in the drawing represent environmental structure only and form no part of the claimed design.

FIG. 4 is a perspective view of our design. The broken lines in the drawing represent environmental structure only and form no part of the claimed design; and,

FIG. 5 is another perspective view of our design. The broken lines in the drawing represent environmental structure only and form no part of the claimed design.

The use of broken lines indicates that the portion of the article depicted in broken lines forms no part of the design, and is not to indicate the relative importance of parts of a design.
